WEATHER INSTRUMENT CASING

Giacinto C. D'Ercoli, Park Forest, Ill., assignor to General
Time Corporation, Stamford, Conn., a corporation of
Delaware

Filed Apr. 18, 1968, Ser. No. 11,512

Term of patent 14 years

Int. Cl. D10—07

U.S. Cl. D52—7

FIG.1

FIG.2

FIG. 4

FIG. 3

FIG. 1 is a front elevational view of a weather instrument casing showing my new design;

FIG. 2 is a rear elevational view;

FIG. 3 is a top plan view; and

FIG. 4 is a right side elevational view.

The broken line showings of dials and hands are for illustrative purposes only.

I claim:

The ornamental design for a weather instrument casing, substantially as shown and described.
